UNITED STATES PATENT OFFICE.

LEWIS J. JAMES, OF WATERBURY, CONNECTICUT, ASSIGNOR TO THE SHOE HARDWARE COMPANY, A CORPORATION OF CONNECTICUT.

COLLAPSIBLE LAST.

Application filed March 28, 1922. Serial No. 547,587.

To all whom it may concern:

Be it known that I, LEWIS J. JAMES, a subject of the King of Great Britain, residing at Waterbury, in the county of New Haven and State of Connecticut, have invented certain new and useful Improvements in a Collapsible Last, of which the following is a full, clear, and exact description.

This invention relates to a collapsible last, 10 more particularly to a last of that type which is shortened by a relative sliding movement of the toe and heel sections in removing it from a footwear article.

Many lasts of the type in which the last 15 is shortened by a relative movement of its toe and heel sections have been devised, and in many of them means are provided for automatically locking the sections when in extended or operative position. However, 20 as far as I am aware, the majority of these require a special tool which must be inserted to unlock the last, and in some instances must be given a special movement, such as a rotary movement, before the last can be 25 unlocked. Moreover, so far as I am aware, in all of the collapsible lasts of the prior art the last must be manually collapsed or extended and merely locks automatically when moved to extended position.

30 An object of my invention is to provide an improved collapsible last.

Another object is to provide an automatically extending last.

Still another object is to provide an automatically extending and locking last.

A further object is to provide a last which may be both unlocked and collapsed in a single operation by the insertion of a tool therein.

40 For a detail disclosure of the invention reference is had to the accompanying specification and drawings, in which latter:

Fig. 1 is a side elevation, partly in section, of one form of my improved last;

45 Fig. 2 is a section on the line 2-2 of Fig. 1;

Fig. 3 is a section on the line 3-3 of Fig. 1;

Fig. 4 is a side elevation, partly in section, of a modified form;

Fig. 5 is a section on the line 5-5 of Fig. 4; and

Fig. 6 is a broken away perspective of the heel section of the last shown in Fig. 4.

55 Referring to the form shown in Figs. 1

to 3, the last body 1 is formed with a toe section 2 provided with an inclined rear wall 3, and if desired fibre or other inserts 2' may be disposed in the sole for tacking purposes. The heel section 4 is provided with an inclined front wall 5, which at its lower end is provided with the rearwardly stepped portion 5' extending to the sole. The inclined wall 3 of the toe section is cut away to form a tapered dove-tail rib 6 widening toward the lower end, which, however, does not extend all the way to the sole, the body of the wall 3 at each side of the lower end of the rib forming stop shoulders 7 for a purpose to be later described. The front 70 wall 5 of the heel section is cut away to form a tapered dove-tail slot 8 in which the dove-tail rib 6 may fit and the lower portion or end of the wall 5 forms stop shoulders 9 at each side of the slot 8 which coact with the stop shoulders 7 on the toe section to limit relative movement of the sections in one direction.

An opening 10 is formed in the wall 3 through the dove-tail rib 6, and a locking 80 and section moving lever 11 is pivotally mounted in said opening on the pivot pin 12. A pair of coil springs 13 are secured to the lever 11 at each side thereof, the other ends of the springs being secured to the 85 rib 6.

These springs tend to normally urge the lever 11 to the position shown in Fig. 1, in which position a cam portion 14 at the lower end of the lever is adapted to engage 90 a wear pin 15 disposed on the face of the stepped portion 5' to lock the sections against collapsing. The use of the wear pin 15 is not essential, but as the lasts are preferably formed of aluminum it is desirable 95 to insert the wear pin to prevent undue wear of the portion 5'. The lever 11 is formed with a notch 16 in its edge, and in the position shown in Fig. 1 a pin 17 secured in the side walls of the heel section 4 is adapted to 100 engage the upper wall of the notch. At its other end the lever is provided with an actuating extension 18 disposed in alignment with an opening 19 in the top of the heel section, through which opening a jack 105 spindle 20 or other tool may be inserted to actuate the lever 11 in opposition to the springs 13.

Referring to the modified form shown in Figs. 4 to 6, the last body 21 is formed with 110

a toe section 22 having an inclined rear wall 23, and a heel section 24 provided with an inclined front wall 25, which wall 25 is provided with a rearwardly offset extension 26 at its bottom. The rear wall 23 of the toe section is cut away to provide spaced and stepped straight dove-tail ribs 27 and 28, that is, the rib 27 is of less width than the rib 28. The rib 28 does not extend all the way to the bottom of the toe section, and the wall 23 forms stop shoulders 29 at each side of the base of the rib. The front wall 25 of the heel section is provided with a slot 30, as shown in Figs. 5 and 6. This slot is dove-tailed on its upper portion as shown at 31 to coact with the dove-tail rib 27, and adjacent its lower end is provided with a wider dove-tail portion 32 to coact with the dove-tail rib 28. The lower end portions of the wall 25 at each side of the slot 30 form stop shoulders 33 which coact with the shoulders 29 to limit the sliding movement of the sections when in extended position.

The wall 23 of the toe section is provided with an opening 34, and secured to the side walls of said opening in the present instance are brackets 35 in which the locking and section-moving lever 36 is pivotally mounted on the pivot pin 37. If desired the brackets 35 may be formed integral with the section 22. A pin 38 projects rearwardly from the lever 36 and one end of a coil spring 39 is connected to said pin, the other end of the spring being connected to a pin 40 secured in the wall 23. It will be seen that this spring tends to normally urge the lever 36 to the position shown in Fig. 4, in which its lower locking end 41 coacts with the shoulder 42 on the extension 26 to prevent the collapsing of the last. The lever 36 is provided with a notch 43, through which passes a pin 44 secured in the side walls of the heel section 24, the pin in the last position shown in Fig. 4 being in contact with the upper wall of the notch. The other end of the lever is provided with an actuating extension 45 disposed in alignment with an opening 46 in the top of the heel section, through which opening a jack spindle or other tool 47 may be inserted to actuate the lever in opposition to the spring 39. In the form shown in Fig. 4 the last is also provided with openings 48 for the reception of the usual last supporting pins.

In the operation of the form shown in Fig. 1 the last when in position in a footwear article is automatically extended and locked in extended position by the action of the springs 13, which move the lever 11 so that the upper wall of its notch 16 contacts with the pin 17 on the heel section, causing the heel and toe sections to be relatively moved until the shoulders 9 on the heel section contact with the shoulders 7 on the toe section, which limits any further

relative movement of the sections in one direction. At this time the cam or locking portion 14 of the lever engages the wear pin 15 as shown in Fig. 1 and prevents any relative movement of the sections in the opposite direction. When it is desired to remove the last from the footwear article the jack spindle or other tool 20 is inserted in the opening 19 and pressed against the extension 18 of lever 11. This first disengages the locking shoulder 14 from the wear pin 15, thereby unlocking the last, and in the further movement of the lever 11 the lower wall of the notch 16 contacts with the pin 17 and moves the heel section on the toe section in the manner shown in dotted lines in Fig. 1. It will be seen that by reason of the lost motion connection of the pin 17 with the lever 11 through the notch 16, in collapsing the last the lever does not tend to relatively move the sections until after they have first been unlocked, while in moving the sections to extended or locked position the lock does not operate until after the sections have been moved to extended position. The operation of the modified form shown in Figs. 4 to 6 is in all respects similar to the operation of the form shown in Fig. 1.

It will be seen that I have provided a simple, easily operated last which is provided with an inclined connection between the heel and toe sections by means of which the last may be foreshortened without first lengthening it, and I have provided a last which is both unlocked and moved to collapsed position by merely inserting a tool therein, and which automatically moves to extended position and locks upon removal of the tool. The necessity of manually collapsing or extending the last in addition to locking and unlocking it is therefore entirely obviated.

With the embodiments disclosed herein many modifications will suggest themselves to those skilled in the art, and I do not desire the scope of the invention to be limited otherwise than as defined in the appended claims.

Having thus described my invention, what I claim and desire to protect by Letters Patent is:

1. A collapsible last comprising movably connected sections, and means wholly within the last for relatively moving them in one direction, the last being provided with an opening in alignment with said first means whereby a tool may be engaged with said first means to relatively move the sections in an opposite direction.

2. A collapsible last comprising movably connected sections, a lever within the last for extending or collapsing the sections, and spring means for imparting one of said movements to the lever, the wall of the last being provided with an opening in alignment with said lever whereby a tool may be

- engaged with the lever to impart to it the opposite movement.
3. A collapsible last comprising slidably connected toe and heel sections, a lever within the last for relatively moving the sections, and a spring urging said lever to extend the sections, one of the sections being provided with an opening in alignment with said lever whereby a tool may be engaged with the lever to actuate it to collapse the sections.
4. A collapsible last comprising movably connected sections, tool operable means within the last for unlocking and collapsing the sections, and means for automatically extending and locking the sections.
5. A collapsible last comprising movably connected sections, means wholly within the last for successively relatively moving them to and locking them in extended position, and means whereby said last named means may be reversely actuated.
6. A collapsible last comprising movably connected sections, and means for successively relatively moving them to and locking them in extended position, said last named means including resilient actuating means.
7. A collapsible last comprising relatively movable sections, means mounted in one section and having section moving and locking engagements with the other section, and means for actuating said last named means.
8. A collapsible last comprising relatively movable sections, means disposed within the last and actuatable in one direction to successively extend and lock the sections and in the other direction to successively unlock and collapse the sections, and means normally urging said first means to extend and lock the sections.
9. A collapsible last comprising relatively movable sections, means mounted in one section and having last extending and locking engagements with the other section, and means wholly within the last for actuating said last named means to successively extend and lock the sections, one section having an opening whereby an instrument may be engaged with said first means to unlock and collapse the sections.
10. A collapsible last comprising movable sections, and a spring actuated lever for relatively moving and locking the sections, the last having an opening whereby a tool may engage the lever to move it in opposition to said spring.
11. A collapsible last comprising relatively movable sections, a lever for moving them to extended position and locking them or unlocking and moving them to collapsed position, and a spring for urging said lever to extending and locking position, the last having an opening formed in its top in alignment with said lever, whereby the lever may be engaged by a tool and moved to un-
- locking and collapsing position in opposition to said spring.
12. A collapsible last comprising relatively movable sections, a lever pivotally mounted in one section and extending into the other and having last extending and locking engagements with the latter, and spring means for moving said lever to extend and lock the last.
13. A collapsible last comprising relatively movable sections, a lever pivotally mounted in one section and extending into the other and having last extending and locking engagements with the latter, one section having an opening whereby an instrument may be engaged with said lever to unlock and collapse the last, and spring means tending to urge said lever to last extending and locking position.
14. A collapsible last comprising slidably connected sections, means wholly within the last for moving the sections to extended position, co-acting stops on adjoining faces of the sections for limiting said movement, and coacting means carried by said first means and one section for locking the sections in extended position.
15. A collapsible last comprising relatively movable sections, a lever pivotally mounted in one section and extending into the second, said lever having an actuating arm, a locking extension and a notch, said second section having a shoulder cooperating with said extension, a pin passing through said notch, and engageable by opposite walls thereof to relatively move the sections, and an opening in alignment with said actuating arm, and resilient means for urging said extension into locking cooperation with said shoulder.
16. A collapsible last comprising sections having an inclined sliding connection, a lever pivoted to one section and having a lost motion section actuating connection with the other, a locking shoulder on the last named section adapted to coact with said lever, and means for yieldingly maintaining said lever in locking relation to said shoulder.
17. A collapsible last comprising two sections having an inclined sliding dove-tail connection, spring actuated means for relatively moving the sections to operative position and locking them, and means whereby said first means may be reversely actuated to unlock the sections and relatively move them to inoperative position.
18. A collapsible last comprising two sections having a sliding dove-tail connection, coacting shoulders on the sections limiting their movement in one direction, means movable in one direction for successively moving said shoulders into engagement and locking them, and an opening in one section whereby an instrument may be engaged

with said last named means to move it in an opposite direction and thereby unlock said shoulders and relatively move the sections.

19. A collapsible last comprising slidably connected sections, means actuatable in opposite directions for successively moving the sections to extended position and locking them or for unlocking and moving them to collapsed position, and yielding means for actuating said first means in one direction, one section having an opening therein whereby an instrument may engage said first means to move it in the opposite direction.
- 15 20. A collapsible last comprising two sections having a slidable dove-tail connection,

a lever pivotally mounted in one section and having a portion adapted to engage the other section and lock it against movement, a notch in said lever, a pin on said other section disposed in said notch and having a lost motion driving connection with the wall thereof, and means for moving said lever to locking position, the last having an opening therein whereby an instrument may be engaged with said lever to move it from locking position and into engagement with said pin to move said other section.

Signed at Waterbury, county of New Haven, and State of Connecticut, this 20th day of March, 1922.

LEWIS J. JAMES.
